UNITED STATES PATENT OFFICE.

ADAM S. LANDIS, OF YORK, PENNSYLVANIA.

DESIGN FOR A HOTEL-SIGN.

44,343.

Specification for Design.

Patented July 15, 1913.

Application filed January 2, 1913. Serial No. 739,891. Term of patent 7 years.

To all whom it may concern:

Be it known that I, ADAM S. LANDIS, a citizen of the United States, residing at York, in the county of York and State of Pennsylvania, have invented a new, original, and ornamental Design for Hotel-Signs, of which the following is a specification, reference being had to the accompanying drawing, forming a part thereof.

The figure is a perspective view of my improved design.

I claim:

The ornamental design for a hotel sign, as shown.

ADAM S. LANDIS.

Witnesses:

NOAH C. MAY,
H. G. MERRILL.
